CLAIM

The ornamental design for a shower handle and escutcheon, as shown and described.

DESCRIPTION

FIG. 1 is a perspective view of a shower handle and escutcheon showing my new design;
FIG. 2 is a front view thereof;
FIG. 3 is a top plan view thereof;
FIG. 4 is a side elevational view, the opposite side being a mirror image thereof; and,
FIG. 5 is a bottom plan view thereof.
